UNITED STATES PATENT OFFICE.

HORATIO B. HOLLIFIELD, OF WASHINGTON, DISTRICT OF COLUMBIA.

ATTACHMENT FOR SMALL-ARMS.

No. 867,728.

Specification of Letters Patent.

Patented Oct. 8, 1907.

Application filed February 6, 1907. Serial No. 355,976.

To all whom it may concern:

Be it known that I, HORATIO B. HOLLIFIELD, a citizen of the United States, residing at Washington, in the District of Columbia, have invented certain new and useful Improvements in Attachments for Small-Arms, of which the following is a specification.

The long practice requisite for becoming an expert marksman usually involves a heavy expense for ammunition, and further necessitates using much time 10 in going to and from suitable places for practice and in noting carefully the result of each shot at a distant target.

The general object of this invention is to save much of the time and money thus expended, although it is 15 not supposed that all actual practice on the range or in the gallery can be dispensed with.

The invention involves the use of inexpensive apparatus that can be readily attached, temporarily, to ordinary small arms to enable the marksman to practice 20 at home and thereby to acquire certain of the primary requisites of a good marksman.

More specifically, the apparatus involves the use of a needle or other target-marking device which is projected beyond the muzzle of the weapon by the force 25 of the firing pin, or the like, when the trigger of the unloaded weapon is pulled, the target to be marked usually being a miniature one fixed a little in front of the weapon.

In the accompanying drawings, Figure 1 is a side 30 elevation of an ordinary service rifle provided with my devices. Fig. 2 is a plan view of the same apparatus. Fig. 3 is an enlarged vertical section through the axis of the rifle barrel. Fig. 4 is a perspective view of devices mounted at the muzzle-end of the barrel. Fig. 5 35 is a like view of a modified form of the devices shown in Fig. 4. Fig. 6 shows, detached, a modified construction of the attachments shown in connection with the barrel in Fig. 3. Fig. 7 shows another modification of the devices to be used at the muzzle end of the barrel.

40 rel.

In these views, A represents the barrel of a common army rifle, A' the front sight upon the same, and B the firing pin actuated in the usual way by means not shown, when the trigger C is pulled. In the cartridge 45 chamber of the barrel is placed an unloaded shell D, of usual form, having fixed in the place of the ordinary projectile an axially perforated plug D' which may be of wood or other suitable material. In the plug slides a small rod E which extends rearward a short 50 distance through the rear end of the shell, in line with the firing pin. Upon the rod, near the rear end of the shell, is fixed a guiding disk and stop E' which slides freely in the shell and in case the rod should move so far forward as to pass out of the aperture in the shell, 55 guides it again into the perforation upon its return. Between this disk and the plug D' is a light spring F

which resists the advance of the rod. The rod extends forward nearly to the muzzle of the gun and at its end it is provided with a block E² which moves freely in the barrel. Obviously when, by pulling the trigger, 60 the firing pin is shot forward, it strikes the rear end of the rod and impels the latter suddenly forward, the spring returning it to position an instant later.

Over the muzzle of the gun is slipped a closely fitting cup-like member G which is slotted on its upper side 65 to receive the front sight A', the latter thus fixing accurately the angular or rotary adjustment of the cup. The bottom of the cup is centrally perforated for the passage of a short loose rod E³ bearing at its inner end a block E⁴ preferably of heavy material and normally 70 held free from but in contact with the block E² by a spring F'. From the lower side of the cup an arm H extends downward and then forward in a direction parallel to the barrel. The rod E³ on passing through the bottom of the cup turns downward to a point below the 75 barrel, then extends rearward, parallel to the barrel, for some distance, then doubles upon itself and passes forward again parallel to the barrel, through the arm H, and finally terminates a little in the rear of the free end of the arm, in a sharp point E⁵, which the arm prevents 80 from doing or receiving injury. The cup may be removably secured to the barrel, if desired, by any suitable means fixing it to the barrel or the sight. The block E⁴ being normally in contact with the block E², when the latter is shot forward by the firing pin, as 85 already described, the block E⁴ and the rod E³ are impelled forward positively to the same extent and are then carried forward by momentum through nearly the whole distance allowed by the bend in the rod, the point E⁵ being thus projected some distance beyond 90 the end of the arm H and then instantly returned to normal position by the spring F'. In thus advancing, the point may perforate a sub-target (not shown) fixed at a short distance in front of the gun.

In order that the gun may be held at the proper distance from such sub-target, a block I is removably fixed to the side of the gun by rings or straps I' and is provided with a laterally projecting rigid arm J having a hook, J', or other suitable device adapted to engage any suitable support. The sub-target is so placed that 95 when the gun is properly aimed at a more distant target, the point E⁵ alines with the center of the sub-target; whence it follows that error in the aim will cause a corresponding deviation from such alinement.

From the construction, it is evident that the whole 100 apparatus may be quickly attached to or removed from the rifle without in any way disfiguring the latter.

Fig. 5 shows the rod E⁶, corresponding to the rod E³ as unbent, the arm H being omitted. This construction has the disadvantage of compelling the use of a 110 very small sub-target, in order that the line of sight to the main target may not be obstructed.

Fig. 6 shows a construction in which the shell D is omitted, a disk E⁷ corresponding to the disk E' being made to fit the cartridge chamber, and the two parts E⁸, E⁹ of the rod being detachably connected, by a 5 threaded sleeve or otherwise.

Fig. 7 shows a detached block K provided with a point K', to be used instead of the devices shown in Figs. 1, 2, 3 as borne by the muzzle end of the gun. In this case, the block is shot forward by the impact of 10 the block E² and is replaced by hand.

Other modifications in construction may be made without passing beyond the proper limits of my invention.

What I claim is:

- 15 1. The combination with a rigid rod adapted to be mounted in the rear portion of the bore of a gun in the path of the firing pin, a spring to urge said rod rearward, a second rod adapted to be slidably mounted in the forward portion of the barrel in alignment with the first rod and provided with a target piercing point, and a guide, for the second rod, adapted to be secured to the muzzle portion of the barrel.
- 20 2. The combination with a sliding rod adapted to be slidably mounted in the rear portion of the bore of a gun in the path of the firing pin, of a spring to resist the forward sliding of the rod under the impact of the firing pin, a second rod adapted to be slidably mounted in the forward portion of the bore in alignment with the first rod and provided with a target piercing point at the muzzle end of the gun, and a spring yieldingly resisting the forward movement of the second rod.
- 25 3. The combination with a gun and a sliding rod mounted in the rear portion of the bore in the path of the firing pin, a second rod mounted in the front portion of the bore, normally abutting the first rod and provided

with a target piercing point offset laterally from the axis of the rod, and a spring yieldingly resisting the advance of the second rod.

4. The combination with a gun, of an unloaded shell fitting the cartridge chamber and provided with a longitudinally perforated plug fitting the bore in front of said chamber, a rigid rod sliding in said plug and extending rearward through the shell in the path of the firing pin, a spring within the shell normally holding the rod in its rearmost position, a second sliding rod located in the 45 forward part of the bore, abutting the first rod and having an offset pointed end projecting in front of the gun, a guide for said projecting end secured to the muzzle of the gun, and a spring resisting the forward movement of the second rod.

5. The combination with a gun, of a centrally perforated cup detachably secured over the muzzle of the gun and provided with a forwardly extending arm below the bore, of a sliding rod lying in the perforation in the cup, extending rearwardly in the barrel, and having a 55 forwardly projecting offset portion in front of the gun, a spring resisting forward movement of said rod, and means whereby the advance of the firing pin impels said rod forward.

6. In target practice attachments for small arms, the 60 combination with a gun, of a rigid lateral projection detachably fixed to the barrel between its ends and adapted to engage a suitable rigid support and hold the muzzle of the gun at a substantially constant distance from a sub-target while leaving the gun free to be aimed, substantially as set forth.

In testimony whereof I have signed my name to this specification in the presence of two subscribing witnesses.

H. B. HOLLIFIELD.
